(57) CLAIM

The ornamental design for a slat for venetian blinds, as shown and described.

DESCRIPTION

FIG. 1 is an isometric view of the front of the slat for venetian blinds.

FIG. 2 is an isometric view similar to FIG. 1 of the rear of the slat.

FIG. 3 is an isometric view of the slat as shown in FIG. 1 having been rotated 90 degrees.

FIG. 4 is a left end elevation of the slat as shown in FIG. 1.

FIG. 5 is a front elevation of the slat.

FIG. 6 is a right end elevation of the slat as shown in FIG. 1.

FIG. 7 is a bottom plan view of the slat.

FIG. 8 is a rear elevation of the slat.

FIG. 9 is a top plan view of the slat.

FIG. 10 is an isometric view of the slat, shown assembled in a venetian blind in an open position.

FIG. 11 is an isometric view similar to FIG. 10 only in closed position; and,

FIG. 12 is a left-side elevation view shown assembled in a venetian blind in an open but retracted position.

The broken line showing is for illustrative purposes only and forms no part of the claim design.
